UNITED STATES PATENT OFFICE.

ELMER A. CLARK, OF JOLIET, ILLINOIS.

METAL FRAME STRUCTURE.

1,169,461.

Specification of Letters Patent. Patented Jan. 25, 1916.

Application filed January 20, 1913. Serial No. 743,041.

To all whom it may concern:

Be it known that I, ELMER A. CLARK, citizen of the United States, residing at Joliet, in the county of Will and State of Illinois, have invented certain new and useful Improvements in Metal Frame Structures, of which the following is a specification.

This invention relates to the construction of metal frames of a rigid character adapted for use as shelves when combined with wires or other frame filling means.

The especial object of my present invention is to provide a rectangular frame made up of angle-bars joined together at their ends without using rivets, bolts or welding.

In the accompanying drawing, I have illustrated a preferred manner of constructing a frame according to my invention in the following views:—

Figure 1 is a plan view of my improved frame; Fig. 2 is a fragmentary view showing in perspective one of the joints of the frame; Fig. 3 is a fragmentary sectional view of the joint shown in Fig. 2; Fig. 4 is a plan view showing my improved frame combined with wires to form a shelf.

Referring to the details of the drawing, it will be seen that the frame is made up entirely of angle-bars, the numerals 5, 5, representing the side members and 6, 6, the end members of a rectangular structure of parallelogrammatic shape.

At each end of the bars 5, one branch or wall of the angle is notched or cut away as at 5^a, to provide a snug fitting seat for the adjacent wall of the other bar 6 which extends at right-angles to the notched branch of the bar 5, when the members are assembled. Said notch is so formed and proportioned that the shoulders left thereby fit squarely the wall of the member seated in said notch so that the flat outer surface of the bar 6 is flush with the edge of the bar 5, as shown in Fig. 3. The ends of the bar 6 are correspondingly notched to receive the bar 5 as shown at 6^a, Fig. 2. Near the ends of the bars 6, and in the notched walls thereof, are punched slots of rectangular shape, to receive the lugs 5^b on the ends of the notched walls of the bars. These lugs are slightly longer than the thickness of the walls which they penetrate, thus leaving

some metal projecting which is headed over to bind the members together. As all the 55 notches and lugs are cut to produce right angled edges and as the angle-bars have true right-angled walls, it will be obvious that the interfitting portions will coöperate to maintain the assembled members in the 60 desired right-angled relation.

The frame structure above described is convertible into a shelf or analogous article, by the application thereto of one or more cross-bars 7, the ends of which are seated 65 and secured in suitable openings in the bars 5, and by wires 8, which are strung longitudinally of the frame, passing through suitable notches 7^a in the bar 7, and have their ends secured in any approved manner in 70 suitable holes 6^b in the end bars 6.

If desired, the cross-bar 7 may have its ends cut to form tongues identical with the tongues 5^b, to fit corresponding holes in the walls of the members 5, as indicated at 7^b. 75

Having thus described my invention, what I claim as new, is:—

1. A joint comprising two angle bars wherein the end and side of a flange of one member is recessed to receive the flanges of 80 the other member, one edge of one flange of the second mentioned member is recessed to receive the unrecessed flange of the first-mentioned member, and one of said members provided with a tongue adapted to engage an aperture in the adjacent portion of the other member.

2. A corner joint consisting of two angle bars, 5 and 6, a portion of the end edge and bottom edge of the vertical flange of the 90 bar 5 being cut away, a tongue extending therefrom, a portion of the top of the vertical flange of the bar 6 being cut away, said vertical flange being provided with an aperture to receive said tongue, the horizontal flange of the bar 5 engaging the cutaway portion of the vertical flange of the bar 6, the vertical and horizontal flanges of the bar 6 coöperating with the cut away portions of the vertical flange of the bar 5. 100

In testimony whereof I affix my signature in the presence of two witnesses.

ELMER A. CLARK.
